ADJUSTABLE DOOR ACTUATING DEVICE
FOR VARYING THE AT REST POSITION

Wallace O. James, Jackson, Mich.

Application June 5, 1946, Serial No. 674,545

2 Claims. (Cl. 16—49)

1

The present invention relates to improvements in door checks and closers being especially adapted to doors which swing in one or both sides of the door frame and capable of holding the door either closed or in any position between fully opened and fully closed.

Fluid door checks and closers which are in extensive use at the present time require frequent maintenance and repair, especially on store and theater doors where they are subjected to excessive use. Moreover, they are of a design which does not readily adapt itself to holding the door in different positions.

According to the present invention, a door check and closer has been provided in which gravity is solely employed to control the movement and position of the door. The mechanism may be conveniently housed in the door structure and adjusted to bring to or hold the door in any desired position.

Thus one of the objects of the invention is to provide an improved control mechanism for doors and the like operated solely by gravity.

Another object of the invention is to provide an improved door check and closer under the control of a weight, actuated by the movement of the door, in which the influence of gravity controls the "at rest" positions of the door.

Another object is to provide an improved door check and closer which is especially adapted for doors which swing to both sides of the door frame.

A still further object of the invention is to provide a door check and closer which is readily adjustable to hold the door "at rest" in any desired position between fully open and fully closed.

These and other objects and advantages residing in the combination, arrangement and construction of parts is more fully disclosed in the following specification and the appended claims.

In the drawing:

Fig. I is a top view showing the mechanism installed in a door structure with the cover plate removed,

Fig. II is a side elevational view of the mechanism shown in Fig. I,

Fig. III is a view similar to Fig. II on a reduced scale showing the mechanism mounted in the door,

Fig. IV is a detail of the lower hinge pin of the door,

Fig. V is a view taken on line V—V of Fig. VI of a modified form of the invention,

Fig. VI is a side elevational view of the door 55 in a modified form of the invention.

2

shown in broken section of a modified form of the mechanism shown installed, and

Fig. VII is a fragmentary side elevational view of the mechanism shown in Fig. VI with the door open.

Referring to the form of the invention shown in Figs. I to IV, inclusive, the check and closer unit comprises a framework 10, which is mounted between the inner and outer panels of the door, and having side plates 12 and transverse members 14, 16 and 18. In Fig. II one of the side plates 12 has been removed as well as one of the large gears for purposes of illustration.

8360<br

When the door is swung in one direction from its "at rest" position, depending upon which direction the door is swung, one of the pins 56 and 58 will be moved from the position *a* indicated in Fig. III, which corresponds to the positions shown in Figs. I and II, into the position *b*, while the other pin will be moved into the position *c*. The pin moved into the position *b* of Fig. III will elevate the arm 24 from the lower dotted line position into the upper dotted line position. When the door is released to the action of gravity acting upon the weight 60 in its elevated position, the action of the arm 24 will rotate the gears 26 and 28 in opposite directions through engagement with whichever of the pins 56 and 58 has been elevated into the position *b* and the door will be swung into its "at rest" position, namely, with both of the pins 56 and 58 brought back into the position *a*. When the door is swung in the opposite direction, the other of the pins 56 and 58 is moved from the position *a* to the position *b* to elevate the weight 60 from the lower dotted line position to the elevated dotted line position shown.

It will be understood through the foregoing description that when the door is in an "at rest" position, the arm 24 is engaging with both the pins 56 and 58 and that any movement of the door from its "at rest" position is opposed by the maximum effectiveness of the weight 60. It will further be appreciated that the "at rest" position of the door may be at any point in its path of movement between fully open and fully closed and this is true regardless of whether the door is swung in only one direction to close or is capable of being swung in two directions as in the case of what is conventionally known as the swinging door.

In Fig. IV, a lower mounting pin constituting a pivot for the door is indicated at 62. The upper end of the pin 62 is provided with a flange 64 against which a spring 66 acts to lift the pin 62 vertically when the eccentric shaft 68, which is supported in the panels of the door, is rotated through the screwdriver slot 70 formed in one end thereof to permit the door to be taken down. At the time of installation of the door, the eccentric shaft 68 is rotated into the position shown in Fig. IV to project the pin 62 into a supporting socket mounted in the floor in vertical alignment with the recess 44.

In the modification shown in Figs. V to VII, inclusive, the door 72 is of a swinging type shown in its closed position within the door frame 74. The lower part of the door has a thrust plate 76 which rotates in the bearing plate 78 mounted in the door sill 80. The plate 78 has a square hole 82 in which a similarly shaped end 84 of a rod 86 is inserted to hold the rod 86 against rotation. It is to be understood that the door swings around the axis of the rod 86. The rod 86 passes through bushing 88 and abuts at its upper end against an eccentric 90 which when rotated out of the position shown will permit the spring 92 acting against the bevel gear 94 to lift the teeth thereof out of engagement with the gear 96. Preferably the construction of the eccentric 90 is such that rotation thereof through approximately 90° from the position shown in Fig. VI is sufficient for the teeth of the gear 94 to clear the teeth of the gear 96. This will permit relative rotation between shaft 86 and the shaft 98 upon which the gear 96 is mounted. When the eccentric 90 is rotated through 180° from the position shown in Fig. VI, shaft 86 is moved vertically a sufficient distance

for the end 84 to clear the hole in the bearing plate 78 to permit the door to be removed from its mounting structure.

The shaft 98 which is slidably mounted in a bearing provided in the door 72 is tubular at one end and of non-circular interior construction in order to receive with a sliding fit a similarly shaped shaft 100 which telescopes with the shaft 98 and is slidably mounted in a bearing provided in the door 72. The extension 101 of the shaft 100 carries a gear 102 against which a spring 104 acts to force the outer end of the shaft 101 against the eccentric 106. When the eccentric 106 is rotated from the position shown through 180° by a suitable key inserted into the opening 108 of the shaft 100, the gear 102 will be moved out of mesh with the ring gear 112 to permit relative movement between the gears 102 and 112.

The gear 112 is mounted for rotation on a stub shaft 114. Attached to and operating as an integral part of the gear 112 is a sheave 116 having an opening 118 through which one end of a flexible cable 120 is extended and anchored. At the opposite end of the cable 120 is a weight 122. As illustrated, the cable 120 passes between a pair of pulleys 124 and 126.

With the door 72 in the closed position shown in Figs. V and VI, the point of anchorage 118 between the cable 120 and the sheave 116 will be at the bottom as indicated in Fig. VI with the cable 120 hanging straight down from the anchorage 118. This is the "at rest" position of the door. If the door is now swung in either direction from the "at rest" position, the shaft 100 is rotated by the swinging movement, which results in rotation of the gear 112 to wind the cable 120 upon the sheave 116 as indicated in Fig. VII. The weight 122 is now in its raised position and is continuously acting to rotate the gear 112 back into the position indicated in Fig. VI. If the door 72 is swung in the opposite direction from that indicated in Fig. VII, it will be understood that the cable 120 will wind up on the opposite side of the sheave 116 from that illustrated.

To alter the "at rest" position of the door 72 from its fully closed position shown in Figs. V and VI, it is only necessary to disengage either the gear 102 from the gear 112 or the gear 94 from the gear 96. This may be accomplished by rotating either of the eccentrics 90 or 106. With the gears 94 or 102 disengaged from their respective meshing gears, by swinging the door 72 from the position shown in Fig. V to any other position and then engaging either of the gears 94 and 102, the "at rest" position of the door will be at that point in which re-engagement of the gears takes place.

It will be understood that swinging the door 72 in either direction will rotate the shaft 86 which through the chain of gearing results in the weight 122 being lifted. Then when the door 72 is released to the energy stored up in the weight 122, it will in turn function to rotate the gear 112 and through the chain of gearing swing the door into its "at rest" position.

Having thus described my invention, what I claim as new and desire to cover by Letters Patents is:

1. In combination with a door supported for swinging movement in opposite directions from its "at rest" position, a door actuator structure mounted in said door comprising a fixed part on which the door swings, a first gear fixed on said part, a shaft, a primary gear on said shaft meshing with said first gear, a second gear on said

shaft, a pair of opposed gears supported for rotation around a common axis and meshing with opposite sides of said second gear and driven thereby in opposite directions, a weight supported for rotation upon said axis, means upon said opposed gears for selectively engaging said weight to elevate the same upon swinging movements of said door in either direction from its "at rest" position, said means collectively supporting said weight in a partially raised position with said door in its "at rest" position.

2. In the combination defined in claim 1, said fixed part being supported for axial movement, and adjustable means for controlling the axial movement of said fixed part to selectively mesh or disengage said first gear with said primary gear to change the "at rest" position of the door.

WALLACE O. JAMES.
